UNITED STATES PATENT OFFICE.

IRA G. PRIDE, OF MEDFORD, MASSACHUSETTS, ASSIGNOR, BY MESNE ASSIGNMENTS,
TO CAROLYN D. IDE, OF WELLESLEY, MASSACHUSETTS.

ORNAMENTAL SHADE.

Application filed February 6, 1926. Serial No. 86,490.

This invention relates to shades for sources of light, and more particularly to ornamental lamp shades. Objects of the invention are to provide an ornamental novelty shade, utilizing wood with its natural grain displayed in an effective and pleasing manner; and to treat a sheet of wood employed in a shade in such a manner as to increase its translucency, durability and flexibility, so that it will display the grain of the wood to better advantage and will resist the effects of moisture and drying and will not be subject to objectionable cracking, distortion and other difficulties; to provide an unformed blank of wood as an article of commerce adapted to be assembled as a shade by the purchaser; and generally to provide an improved and ornamental form of article of the kind referred to.

In accordance with one aspect of the present invention, a translucent sheet of wood is supported to intercept the rays from a source of light thereby to display the physical structure of the wood when the adjacent fibres thereof are in substantially their original natural relationship. A fixing substance applied to the sheet of wood renders the wood translucent or increases its translucency, and increases its flexibility and durability so that it will resist the effects of moisture, drying, and other factors. A diaphanous medium such as a translucent sheet of fabric adhering to the back of the sheet of wood serves to retain the adjacent fibres of the wood in substantially their original natural relationship, and to prevent cracking, distortion and other difficulties resulting from the tendency of different parts of the wood to unequally expand or contract, or resulting from bending the wood.

In one form of the invention a translucent sheet consisting of a ply of wood and an adhering ply of fabric is formed into a loop, the ends of the loop being fastened together. By disposing the fibres of the wood in a direction similar to that of the plane of the loop, the strength and durability of the shade are much greater than when the fibres are disposed in other positions, and the form of the shade is more conveniently maintained. A reinforcing and supporting ring may be provided at the margins of the shade by applying a relatively stiff strip of U-shaped or other suitable cross section to the exposed edges of the sheet.

These and other objects and features of the invention will be understood more clearly in view of the following detailed description and the accompanying drawing, in which:

Fig. 1 is an elevation of a lamp shade and stand;

Fig. 2 is a vertical section of Fig. 1;

Fig. 3 is a plan of the upper edge of Fig. 2.

Fig. 4 is an enlarged fragment, partly in section of a modified form of shade; and

Fig. 5 is an unformed blank for a shade.

Referring to Fig. 1, the shade 1 supported on the base 2 of conventional form, is illuminated by the electric lamp 3, shown in dotted lines, or by any other suitable source of light. The shade consists of a sheet of wood of such thinness that it is translucent, or of such thinness that when treated to reduce its opacity it is appreciably translucent. In the case of many kinds of wood, it has been found that a sheet having a thickness as great as fifteen thousandths of an inch or greater may be suitably translucent, while sheets of less thickness are more translucent. It will, of course, be understood that the character of the wood and the elements associated therewith in any given case will determine what thickness is required for a given degree of translucency.

A backing ply 4 of diaphanous material such as paper, cloth, or other suitable medium, which may be either translucent or transparent, is cemented to the wood ply 1 by means of translucent paste or other suitable cement. The plies 1 and 4 together form a translucent sheet which, in the example here referred to, is formed or bent into a shape corresponding to the frustum of a cone by making a loop of a sheet having the shape shown in Fig. 5, and fastening the ends together by translucent paste or other suitable cement, as indicated by lines 5, Fig. 2. The fabric 4 is adapted to resist unequal expansion or contraction of different parts of the wood, and to resist the effects of forces set up by bending the wood.

The grain of the wood is preferably so disposed in the ply that the fibres are directed similarly to the plane of the loop or to the direction of maximum bending as indicated roughly by the direction of the dashes depicting the grain in Figs. 1 and 5. Ornamental bands 6 and 7 may consist of strips of wood ply 1 or may be of other or-

namental nature. These bands are pasted or otherwise secured to the upper and lower edges of the loop by translucent paste or cement for reinforcing the sheet and for 5 ornamental effect. The loop is retained in a circular form by means of stiff circular rings 8 and 9 of U-shape or broken circular cross section, or of any other suitable form. The exposed edge formed by plies 1, 4, and 10 7 is inserted between the arms of the U, and the arms of the U are then clinched at intervals or throughout the extent of the rings as by spinning or by forming under pressure. Rings 8 and 9 may be made of steel 15 or any other suitable material. Spring loops 10 and 11 held in position by ring 12, are supported by attachment to ring 8 by welding or other means at points 13. These loops are adapted to grasp the top of bulb 3, 20 in wellknown manner. It is obvious that any other suitable means may be employed in place of elements 10, 11, and 12.

Fig. 5 shows an unformed blank 14 adapted to be sold in the form indicated or in 25 other suitable form for assembly by the purchaser. The blank consists of a sheet of translucent wood 15, shown broken away to expose the underlying adhering sheet 16 of diaphanous fabric such as paper, cloth, or 30 the like similar to ply 4, Fig. 2. When assembled, the blank may be decorated in any desired manner by braid (not shown) or other well known forms of ornamentation. The blank illustrated has the shape of a 35 sector of an annular ring and is adapted to be assembled in the manner illustrated in Figs. 1 and 2, or Fig. 4, use being made of rings 8 and 9 or any other suitable edge reinforcing or supporting means. It will be 40 noted that the modification of the shade shown in Fig. 4, is similar to the form shown in Fig. 2, but differs therefrom in omitting band 6 or 7.

If desired, the wood may be rendered 45 more flexible and conformable to the supporting rings 8 and 9 of the shade, or to the desired shape, by applying to the wood in any suitable manner, a solution of one or more parts of glycerine and 100 parts of 50 water, the excess liquid being removed from the wood, as by wiping, for example.

It has been found desirable, and usually 55 essential, preferably after the sheet of wood has been formed to the desired shape of shade and the various parts thereof are secured together, and the paste and other parts dried, to apply a fixing and opacity reducing substance, preferably liquid, to the portions 1 and 4 of the shade to render them 60 translucent in the case of a shade made of wood so thick as normally to be opaque or to increase their translucency in the case of a shade made of wood so thin as normally to be translucent. Other functions of the 65 liquid are to cause the wood to display its

grain structure in more detail, to soften the wood and to increase the durability, flexibility, and permanency of the shade, so that it will resist the effects of moisture and drying, and will not be subject to distortion, 70 objectionable cracking, or to other deterioration when subjected to handling and to atmospheric conditions. An example of a fixing liquid found to give suitable results, 75 consists of 2 parts kerosene, 2 parts of linseed oil, and 1 part of drier, with the possible addition of a perfume to counteract objectionable odor.

Considerable variation is possible in the 80 choice of the kind and proportion of the constituents of the fixing liquid. The kerosene appears to serve as an agent for acting on the natural oil or sap in the wood and for softening the wood to render it more flexible, whereas the linseed oil serves to seal the 85 pores of the wood to resist the effects of moisture and drying and to render the effect of the kerosene more permanent. Other constituents having like properties to those 90 named may be substituted.

A pleasing ornamental effect is produced 95 by sheet 1, owing to the intricate natural patterns in the wood as displayed after treatment with the liquids, described above, and as a result of the natural coloring of the wood and the soft light effects produced by unequal diffusion and refraction in different parts of the wood. The larger pores of the wood provide points of greater 100 translucency giving the appearance of numerous independent sources of light. The translucent backing ply 4, Fig. 1 and ply 16, Fig. 4, diffuse light transmitted to the shade so that a more even illumination of the wood is produced.

Owing to the presence of alternate grains or streaks of different translucency in the wood, usually disposed at various angles to the outer surface of the wood, as indicated by lines 17, Fig. 4, the light in going from 110 the source through ply 16, encounters a less translucent layer 17, causing it to be diverted from its original direction of propagation by internal reflection and refraction in the wood, thus producing a highly ornamental 115 effect apparent from the outside of the lamp shade, this effect being quite different from that obtainable in a shade having only superficial pigmentation or indicia.

Various modifications of the species of 120 shade disclosed to illustrate the generic principles of the present invention will be apparent to one skilled in the art. For example, the wood may be dyed any suitable color and the backing ply 4 or 16 may be 125 colored separately and differently from the wood. The blank 14 may obviously be given a different predetermined contour suitable for constructing a different form of shade.

Features of the invention believed to be 130

novel are set forth in the appended claims.

I claim:

1. In a shade of the character described, a translucent sheet of wood, a diaphanous sheet of fabric cemented to one side of said wood sheet, and a substantially permanent wood-softening and impregnating material applied to said wood sheet.
2. In a shade of the character described, a translucent sheet of wood, a diaphanous sheet of fabric cemented to one side of said wood sheet, and an impregnating material applied to said wood sheet, said material containing a wood-softening constituent and a constituent adapted to render the effect of said wood-softening constituent substantially permanent.
3. In a shade of the character described,

a translucent sheet of wood, a diaphanous sheet of fabric cemented to one side of said wood sheet, and an impregnating material applied to said wood sheet, said material containing a kerosene-like liquid and a linseed-oil-like liquid.

4. In a shade of the character described, a thin sheet of wood, a sheet of fabric cemented to one side of said wood sheet, said sheets being capable of being diaphanous when an impregnating material is applied thereto, and a substantially permanent wood-softening and impregnating material applied to said sheets.

In witness whereof, I hereunto subscribe my name this 4th day of February, 1926.

IRA G. PRIDE.
